UNITED STATES PATENT OFFICE.

WILLIAM G. SLAUSON, OF MIDDLETOWN, NEW YORK.

STEREOTYPE-PLATE HOLDER.

SPECIFICATION forming part of Letters Patent No. 398,852, dated March 5, 1889.

Application filed December 27, 1887. Serial No. 259,169. (No model.)

To all whom it may concern:

Be it known that I, WILLIAM G. SLAUSON, residing at Middletown, in the county of Orange and State of New York, have invented 5 certain new and useful Improvements in Stereotype-Plate Holders, of which the following is a specification, reference being had therein to the accompanying drawings.

This invention relates to stereotype, electrotype, printing, and other plate holders; and it consists in the construction and arrangement of parts necessary to produce a plate-holder of the character hereinafter pointed out, and described in the claims.

15 The object of this invention is to produce a plate-holder which may be made of any suitable material, and which may be either movably attached to a printing-press or may form a part of the same for the purpose of 20 holding printing or other plates of any required form or size.

In the drawings, Figure 1 is a plan view of a sectional holder having four sections or squares assembled with plates thereon, one 25 plate not being secured. Fig. 2 is a transverse section of a plate-holder, the plate omitted, showing one form of the filling-bars in section and a catch in elevation. Fig. 3 is a broken section showing a catch in section. 30 Fig. 4 is a section of the spring-follower of the holding-catch. Figs. 5 and 6 are modifications of holding-catches and carriers, Fig. 5 being a plan of the form shown in Fig. 4. Fig. 7 is a cross-section of Fig. 4, and Fig. 8 35 is a cross-section of a nearly cylindrical filling-piece without the holding-catch.

A indicates a printing-plate of the ordinary thickness, having beveled edges.

B indicates a section of plate-holder, being 40 the unit of design on which the entire holder is constructed, each unit having face-grooves D at a fixed angle with the side of the same, (the angle in this case being forty-five degrees.) The face-grooves are open at the surface of 45 the holder, but are preferably undercut, as at F, and are formed by slotting perpendicularly to the face of the holder, and then passing a drill, milling, or other proper tool along the slot below the surface in such a way that the 50 under-cut is everywhere at the same distance from the surface of the holder. The grooves pass through the entire holder, which may be

made in sections, the grooves being continuous.

For economy of construction and convenience of use the grooves are preferably cut at the angle described and at equal distances apart, which will bring them at right angles to each other, thus forming perfect squares. 55

The unit of the holder grooved in this manner, whatever may be the angle of the grooves, will always be a rectangle. The grooves will be of equal length in the unit and will meet at the middle of its sides. Sections may consist of one or more of these units. 60

In holders with continuous grooves a filler-piece, E or E², may be passed through the grooves, and if the holder be composed of several sections the filler will tend to bind them together and hold against lateral strains. 65 The filler may fill the grooves under the printing-plate, which will then have solid bearings, when no amount of pressure can compress the plate into the grooves. The perpendicular slot extends a little deeper than the enlarged groove and is narrower, so that the bottom of the cut has a narrow channel running lengthwise thereof, as at S. This flat-bottomed channel will receive the pressure of 70 the set-screw used and prevent the marring 75 of the grooves.

The filling-pieces E are made high enough to exactly fill the grooves in the holders. They may be made, however, to merely fit the perpendicular groove, as in Fig. 2, without 80 reference to the under-cut, when the purpose is merely to fill the opening of the groove at the surface.

A set-screw, F', may be passed through the filling-piece when the same enters under the 85 under-cut in the block, and by driving down on the screw the undercut filling-piece will be firmly pressed against the overhang at the upper part of the groove. (See Fig. 3.) This form of filler is used as a holder for the block-clasps. 90

The filling-piece E may have claws or catches 95 L permanently attached and extending above the face of the holder, the clasping-face of the catch being placed parallel with the sides of the printing-plate. When the claws are so arranged, the filling-pieces are slipped lengthwise in the grooves until the catches hold the plate in proper position, when the filling- 100

pieces are clamped by driving in set-screws, as shown in Fig. 3.

In Fig. 6 I show a two-sided catch, M. These catches M have two holding sides or hooks, 5 and can be placed between two plates so as to hold both on the holder. The pieces L may be swiveled to the holders or carriers E, as shown at L', and will then accommodate themselves to the sides of an irregular plate. The 10 catch L or M has its edges above the holder in position to correspond with the bevel of the printing-plate. The filler-piece E, which carries the catch, may be in two parts, E E', Fig. 4, with an interposed spring, R. The 15 part E' will then yield slightly when secured to the plate. By turning up the screw F' the pin E can be held firmly in any position along the line of the groove, and the catch thus held against the plate. The surface of the 20 holder, after being dressed to its desired finish, is ruled in small squares, preferably to some standard gage, as printers' pica, so that the plates may be readily located in their proper places without the necessity of measurement. 25 On a flat plate the lines will be parallel to its four sides, and on a cylinder they will go with its circumference and across it; in both cases always at right angles to each other, so that the plates can be gaged by the lines, which 30 are numbered, to exact positions on the entire surface and perfect register secured. When the spring R is used, it will give a slight elasticity to the holding-catch, and if the spring be compressed when first adjusted 35 will act as a follower to take up wear.

This block may be made in any number of sections, so as to fill the entire bed of a press, or any portion thereof. The printing-plate can be placed in any position on the press-bed, and by using swiveled catches any form 40 of plate may be held firmly. The perpendicular slot or channel is first cut or milled in the block. Then the grooves may be formed with a drill of a little less diameter than the 45 depth of the channel. The drill does not quite reach to the bottom of the channel, and thus has equal resistance on opposite sides and will work evenly. The narrow channel at the bottom of the groove receives the ends 50 of the set-screws and will catch small particles, leaving the main groove clean and free from blemishes.

I claim—

1. A stereotype-plate holder consisting of a number of rectangular grooved sections, the 55 grooves extending continuously through the sections and so located in adjacent sections as to register at the edges of the sections.

2. The combination, with a grooved plate-holder, of adjustable and detachable filling-pieces entering said grooves, said filling-pieces resting on the bottom of the grooves and extending to the top of said grooves and being flush with the surface of the block, substantially as described. 60

3. The combination, with a holder having undercut grooves and a channel at the bottom thereof, of a filling-piece bearing against the upper shoulders of the groove, and a set-screw passing through the filler and bearing in a 70 channel in the lower portion of the groove. 65

4. A stereotype-plate holder made in sections having a series of intersecting grooves, the unit of whose design is a rectangular unit of any adopted length and width, each unit 75 having four diagonal grooves across its face, all of equal length, the opposite ones parallel, the grooves meeting at the middle of the respective sides of said unit.

5. The combination, with a holder of the 80 character described having undercut grooves, of a swiveled clasping-piece on a follower in this groove, and a set-screw holding the follower in the groove independently of the clasping-piece. 85

6. A stereotype-plate holder of the character described, having an enlarged groove and a perpendicular slot extending a little deeper than said groove, as set forth.

7. A holder having a groove therein, a two-part follower in the groove, having a holding-catch thereon, the two parts of the follower being held apart by a spring, and a fastening device for the rear section of the follower, all in combination, substantially as described. 90 95

In testimony whereof I affix my signature in presence of two witnesses.

WILLIAM G. SLAUSON.
